(57) CLAIM

The ornamental design for a bake ware handle, as shown and described.

DESCRIPTION

FIG. 1 is a front view of a bake ware handle showing my design;

FIG. 2 is a rear view thereof;

FIG. 3 is a side view thereof;

FIG. 4 is an opposite side view thereof;

FIG. 5 is a top view thereof;

FIG. 6 is a bottom view thereof; and,

FIG. 7 is an isometric side view thereof.

The portions of the article shown in broken lines form no part of the claimed design.
